[57] CLAIM

The ornamental design for a jewelry setting for earring, finger ring or pendant, as shown and described.

DESCRIPTION

FIG. 1 is a perspective view of a jewelry setting for an earring showing my new design;

FIG. 2 is a front elevational view;

FIG. 3 is a rear elevational view;

FIG. 4 is a left side view;

FIG. 5 is a right side view;

FIG. 6 is a top plan view;

FIG. 7 is a bottom plan view;

FIG. 8 is a perspective view of a second embodiment of FIG. 1 showing the jewelry setting for a ring; and,

FIG. 9 is a top plan view of a third embodiment of FIG. 1 showing the jewelry setting for a pendant.

The broken lines in FIGS. 1, 2, 8 and 9 are for purposes of illustration only and form no part of the claimed design.
